(57) **CLAIM**

The ornamental design for a protective cover skin for electronic device, as shown and described.

DESCRIPTION

FIG. 1 is a front, top, and right perspective view of a protective cover skin for electronic device, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an exploded front, top, and right perspective view thereof with a top portion open in use.

The broken lines shown in FIGS. 3 and 7 depict parts of the protective cover skin for electronic device, but form no part of the claimed design. The broken lines shown in FIG. 8 depict environment and form no part of the claimed design.

1 Claim, 7 Drawing Sheets
